UNITED STATES PATENT OFFICE.

FRED O. WILLIAMS, OF BROOKLINE, MASSACHUSETTS, ASSIGNOR TO UNITED DRUG COMPANY, OF BOSTON, MASSACHUSETTS, A CORPORATION OF MASSACHUSETTS.

DESIGN FOR A WATER-BOTTLE, SYRINGE-BAG, OR SIMILAR ARTICLE.

50,144.

Specification for Design.

Patented Jan. 2, 1917.

Application filed October 31, 1916. Serial No. 128,797. Term of patent 7 years.

To all whom it may concern:

Be it known that I, FRED O. WILLIAMS, a citizen of the United States, residing at No. 9 Strathmore road, Brookline, in the county of Norfolk and Commonwealth of Massachusetts, have invented a new, original, and ornamental Design for a Water-Bottle, Syringe-Bag, or Similar Article, of which the following is a specification, reference being had to the accompanying drawing, forming part hereof.

The figure is a plan view of a syringe bag, showing my new design.

I claim:

The ornamental design for water bottle, syringe bag, or similar article, as shown.

Dated: September 29, 1916.

FRED O. WILLIAMS.

Witness:

MARCUS E. MAHON.
